INTERMITTENT FEED CHANGE
MECHANISM

Secondo L. Casella, Brooklyn, N. Y., assignor to
Morey Machinery Co., Inc., Astoria, Long Is-
land, N. Y., a corporation of New York

Application November 13, 1942, Serial No. 465,814

10 Claims. (Cl. 74—124)

1 This invention relates to intermittent feed mechanisms and more particularly to such mechanisms effecting the carriage feed in metal shapers, although not so limited.

One object of the present invention is a variable throw of the feed through an infinite number of changes in throw within prescribed limits while the machine is in operation.

Another object of the invention is the utilization of the full throw of a cam in effecting each variation in the movement of the feed.

Another object of the invention is to avoid all shock to the moving parts, this through the instrumentality of a constantly operating cam.

Another object of the invention is the provision of instrumentalities providing for an infinite number of gradations of feed within given limits.

These and other objects of the invention and the means for their attainment will be more apparent from the following detailed description, taken in connection with the accompanying drawings illustrating one embodiment by which the invention may be realized and in which:

Figure 1 is a view showing a shaper to which the carriage feed transmission mechanism of this invention is applied;

Figure 2 is a view in vertical section showing the carriage feed transmission mechanism of this invention;

Figure 3 is a transverse sectional view taken in the plane indicated by the line 3—3 of Figure 2 and looking in the direction of the arrows;

Figure 4 is a transverse vertical sectional view taken in the plane indicated by the line 4—4 of Figure 3 looking in the direction of the arrows; and

Figure 5 is a fragmentary view in perspective showing the coacting instrumentalities by which the feed is initiated and controlled.

Referring first to Figure 1, a shaper, in its entirety, is shown having the ram 10 and carriage 12, as will be understood. The feed is effected by the shaft 14 controlled and actuated by instrumentalities within the housing 16, 18, carried on the base of the ram 10 convenient to the hand of the operator, the degree of feed of the carriage 12, for instance, being determined by the hand lever 20.

Referring now also to Figures 2 and 4, a constantly rotating shaft 22 is provided, which is driven from any convenient source of power, preferably from another moving part of the machine. Shaft 22 is journalled in an anti-friction bearing shown as the ball bearing 24, 25 mounted

2 in the closure 16 forming a part of the housing 16, 18 of the mechanism. The shaft is held in position in the ball race 25 by a lock nut 21. Keyed as at 29 to the lowermost end of the shaft 22 is a hub member 31 to which a cam 33 is secured in proper position as by the screw 35. The cam 33 is thus also constantly rotating.

Journalled in the lower end of hub member 31 and coaxial with the shaft 22, as within an anti-friction bearing 37 is the upper end of a driven shaft 39, the other end of which is suitably supported by an anti-friction bearing 43 carried in a collar 45 supported from the housing section 18. The shafts 22 and 39 are in axial prolongation of one another but are independent, in that the shaft 39 is rotated only indirectly from the shaft 22 in a manner which will be apparent from the following description.

Mounted on the driven shaft 39 is a pinion 47 which is free for rotation about the shaft 39 and is in mesh with a toothed segment 49. The toothed segment 49 is carried upon the end of an arm 51 (Figure 5), forming part of a bell crank lever-like structure 51, 53 shown in plan in Figure 3. The extremity of the other arm 53 of the bell crank lever 51—53 has, pivotally mounted thereon, a stud shaft 55 on which is journalled a shoe 57 sliding in a downwardly facing groove 59 in an arcuate or elongated member 61 which is pivotally supported on a shaft 63 depending from the housing closure 16. The bell crank is fulcrumed on a stud shaft 65 mounted on an adjustable sector 67 for rotation about the axis of drive shaft 22. Sector 67 is supported and moved on spaced horizontal tracks 69 and 71 and retained in position by gibbs 69' and 71', removable, as by the screws 73, in the interest of manufacture and assembly. The sector is formed on its outer periphery with a rack 75 shown best in Figures 2, 3 and 5 and is adjustable along these tracks by a pinion 77 on a shaft 79 rotatably mounted in the cover member 16 and turned, in adjustment, through the instrumentality of the worm 81 on shaft 83 carrying the handle 20. The end of the shaft 79 carries a dial 80 graduated to show the degree of adjustment of the feed.

As shaft 22 rotates, and the cam 33 therefore also rotates, the cam 33 engages a roller 85 rotatably mounted on a stud shaft 87 extending upwardly from a boss 89 on the edge of the top surface of the arcuate member 61 formed in its lower surface with the downwardly facing groove 59. The grooved member 61 is pivoted for oscillation in a horizontal plane on a shaft 63 which is rotatably mounted and suspended in bearings in

the cover 16. The grooved member 61 is normally urged into contact with the cam 33 by a push rod 93 whereof the head 95 is pivoted, as on stud 97, on the upper solid face of the grooved member 61. The push rod 93 is slidable in a bushing 99, 5 removably carried in the wall of the upper housing portion 16, there being a spring 101 between the head 95 of the plunger 93 and the bushing 99 to urge the stud 97 and thereby the roller 85 supported on the end of the grooved member 61 10 into the path of the cam 33.

Pinion 47, as pointed out hereinbefore, is not fastened to the driven shaft 39. It is keyed, as at 103, to a sleeve 105 which is concentric with the shaft 39 and has a downwardly and outwardly extending skirt portion 107 terminating in an outwardly directed flange 109 having therebelow a circular rib or shoulder 111 spaced inwardly of the edge of the skirt 107. A supporting disc 113 is also carried on a shoulder 115 on the lower portion of shaft 39. This disc 113 has an upwardly extending rib or annular shoulder 117 in the same cylindrical plane as shoulder or rib 111 and positioned by the shoulders. Mounted between the flange 109 and the rim of disc 113, 15 is an annular collar 119 and within the annular collar 119 is the outer clutch element 121 of an overrunning clutch comprising the inner clutch element 123 which is keyed to shaft 39. It will be recognized that when the element 121 is rotated in one direction, the shaft 39 is caused to rotate in the same direction through the instrumentality of the rollers 125 coating with the clutch surface members 121, 123. If, on the other hand, the element 121 rotates in the opposite direction, no drive with shaft 39 is effected between the pinion 47 and the shaft 39 because the outer clutch member 121 and skirt 107 are rotated in the same direction and release these parts under the influence of the spring 101. When, however, the shaft 39 is rotated through a predetermined angle it causes the rotation, through the instrumentality of the bevelled pinion 127, of the combined bevelled gear 129 and clutch element 145, 20 which is keyed to the sleeve 135 which is rotatably mounted on shaft 131. Shaft 131, an extremity of which is connected to the shaft 14 through coupling 133, may be selectively connected with the gear 129 for intermittent actuation of shaft 131 and the table. The clutch sleeve 147 is keyed to shaft 131. By moving sleeve 147 to the left (as viewed in Figure 2), the clutch surfaces 146 and 145 are engaged. Such movement of the clutch sleeve is shown as effected by the arm 149 on the shaft 151 and operated by the handle 153 (Figure 1).

The same clutch mechanism may, selectively, be utilized to effect continuous operation of the carriage.

The shaft 155 is continuously rotating, say 60 from the prime mover of the machine and carries the bevelled gear 157 meshing with the bevelled gear 159 keyed, as at 161, to a sleeve 162 on the shaft section 163. The sleeve 162 carries the clutch face or clutch teeth 165 selectively engaging the clutch facing or clutch teeth 167 on the end of the reciprocable clutch sleeve 147 opposite to the clutch face 146.

Provision is also made for braking the sleeve section 135. The sleeve 135 is keyed as at 137 to a brake drum 139 which is encircled by a spring-pressed brake band 141 which can be tightened to the desired degree by the screw 143 to prevent overrunning of the sleeve 135 and the train of mechanism rotating the same.

Shaft section 163 may also be utilized to operate a force feed oiling system. A cam 170 on the end of the shaft may actuate the spring pressed plunger 172 of a pump.

The train of mechanism described above extending from the bevelled pinion 127 through the coupling 133 is not specifically claimed herein as it is the subject matter of claims in my divisional application filed November 16, 1943, Serial No. 510,561.

The operation of the device will be apparent from the foregoing description. Suffice it to say that the driven shaft 39 which in turn actuates the moving element such as the carriage, is rotated through a predetermined angle determined by the angle through which the arm 51 of the bell-crank turns in rotating the pinion 47. The angle through which the arm 51 moves is in turn dependent on two factors. One factor is the position of the shoe 57 in the groove 59. Obviously, the further away the shoe 59 is from the axis 63 of rotation or arcuate movement of the grooved member, the longer will be the arcuate movement of the end of the arm 53 of the bell-crank and hence of the arm 51 thereof and the toothed segment 49 which rotates driven shaft 39. This is because the movement of the end of the grooved member 61 about its pivot is always constant by reason of the effective length of the cam 33 but the path or degree of movement of the shoe about the pivot of the bell-crank member becomes progressively shorter as the shoe is moved in the groove toward the pivot of the grooved member 61. Thus by moving the fulcrum point 65 of the bell crank toward the fulcrum point 63 of the grooved member, the stroke is automatically increased. By the provision of the mechanism described an infinite number of gradations of feed is obtained. All gradations of feed utilize the full stroke of the cam but restrict its effectiveness to correspond to the feed required.

This invention distinguishes over the prior art in that the variable throw of the carriage feed transmission mechanism is effected through an infinite number of changes in throw while the machine is in operation and in each instance utilizing the full throw of a single cam as distinguished from all other known instrumentalities for this purpose which rely on the use of only a portion of the movement of the actuating device, whether cam or other device. By the provision of a constantly operating cam as the actuating instrumentality, a smooth movement is possible devoid of all shock to the moving parts. At the same time, the overrunning clutch between the power input and the power output makes possible an infinite number of gradations of feed, i. e., as low, for instance, as one ten-thousandth of an inch.

Various modifications will occur to those skilled in the art in the configuration and disposition of the component elements going to make up the invention as a whole as well as in the selection of instrumentalities performing the same function in a different manner and no limitation is intended by the phraseology of the foregoing description or illustrations in the annexed drawings except as indicated in the appended claims.

What is claimed is:

1. In feed change mechanism, in combination, a power shaft, a cam on the power shaft, a driven shaft, a gear loosely mounted on the driven shaft, one-way clutch means between the gear

and the driven shaft, a toothed sector, means to support the toothed sector for movement in an arcuate path about the axis of the power shaft, a bell crank pivotally mounted on the toothed sector, a toothed segment on one arm of the bell crank and in mesh with the gear on the driven shaft, a shoe pivotally mounted on the end of the other arm of the bell crank, an arcuate member formed with a groove in its lower surface, means to pivotally mount one end of the arcuate member, means normally urging the other end of the arcuate member toward the cam, said groove receiving the shoe on the bell crank, and a roller pivotally mounted on the other end of said arcuate member for intermittent actuation by the cam whereby said arcuate member is oscillated about its pivot to move the shoe in an arcuate path about the axis of the bell crank pivot to oscillate the bell crank and thereby the driven shaft through an angle proportional to the arc of movement of the shoe.

2. In feed change mechanism, in combination, a power shaft, a cam on the power shaft, a driven shaft, a gear loosely mounted on the driven shaft, one-way clutch means between the gear and the driven shaft, a toothed sector, means to support the toothed sector for movement in an arcuate path about the axis of the power shaft, a bell crank pivotally mounted on the toothed sector, a toothed segment on one arm of the bell crank and in mesh with the gear on the driven shaft, a shoe pivotally mounted on the end of the other arm of the bell crank, an arcuate member formed with a groove in its lower surface, means to pivotally mount one end of the arcuate member, means normally urging the other end of the arcuate member toward the cam, said groove receiving the shoe on the bell crank, and anti-friction means mounted on the other end of said arcuate member for intermittent actuation by the cam whereby said arcuate member is oscillated about its pivot to move the shoe in an arcuate path about the axis of the bell crank pivot to oscillate the bell crank and thereby the driven shaft through an angle proportional to the arc of movement of the shoe.

3. In feed change mechanism, in combination, a power shaft, a cam on the power shaft, a driven shaft in prolongation of the power shaft, a gear loosely mounted on the driven shaft, one-way clutch means between the gear and the driven shaft, a toothed sector, means to support the toothed sector for movement in an arcuate path about the axis of the power shaft, a bell crank pivotally mounted on the toothed sector, a toothed segment on one arm of the bell crank and in mesh with the gear on the driven shaft, a shoe pivotally mounted on the end of the other arm of the bell crank, an arcuate member formed with a groove in its lower surface, means to pivotally mount one end of the arcuate member, means normally urging the other end of the arcuate member toward the cam, said groove receiving the shoe on the bell crank, and a roller pivotally mounted on the other end of said arcuate member for intermittent actuation by the cam whereby said arcuate member is oscillated about its pivot to move the shoe in an arcuate path about the axis of the bell crank pivot to oscillate the bell crank and thereby the driven shaft through an angle proportional to the arc of movement of the shoe.

4. In feed change mechanism, in combination, a power shaft, a cam on the power shaft, a driven shaft, a gear loosely mounted on the driven shaft,

one-way clutch means between the gear and the driven shaft, a sector, means to support the sector for movement in an arcuate path about the axis of the power shaft, a bell crank pivotally mounted on the sector, a toothed segment on one arm of the bell crank and in mesh with the gear on the driven shaft, a shoe pivotally mounted on the end of the other arm of the bell crank, an arcuate member formed with a groove in its lower surface, means to pivotally mount one end of the arcuate member, means normally urging the other end of the arcuate member toward the cam, said groove receiving the shoe on the bell crank, and a roller pivotally mounted on the other end of said arcuate member for intermittent actuation by the cam whereby said arcuate member is oscillated about its pivot to move the shoe in an arcuate path about the axis of the bell crank pivot to oscillate the driven shaft through an angle proportional to the arc of movement of the shoe.

5. In feed change mechanism, in combination, a power shaft, a cam on the power shaft, a driven shaft, a gear, operative connections between the gear and the driven shaft, a sector, means to support the sector for movement in an arcuate path about an axis, a bell crank pivotally mounted on the sector, a toothed segment on one arm of the bell crank and in mesh with the gear operatively connected with the driven shaft, a shoe pivotally mounted on the end of the other arm of the bell crank, an arcuate member formed with a groove in its lower surface, means to pivotally mount one end of the arcuate member, means normally urging the other end of the arcuate member toward the cam, said groove receiving the shoe on the bell crank, and means on the other end of said arcuate member for intermittent actuation by the cam whereby said arcuate member is oscillated about its pivot to move the shoe in an arcuate path about the axis of the bell crank pivot to oscillate the driven shaft through an angle proportional to the arc of movement of the shoe.

6. In feed change mechanism, in combination, a first shaft, cam means on the first shaft, a second shaft, a gear, operative connections between the gear and one of the shafts, a sector, means to support the sector for movement in an arcuate path about an axis, a bell crank pivotally mounted on the sector, a toothed segment on one arm of the bell crank and in mesh with the gear, shoe means mounted on the end of the other arm of the bell crank, an arcuate member formed with a groove receiving the shoe means on the bell crank, means to pivotally mount one end of the arcuate member and means normally urging the other end of the arcuate member toward the cam, said arcuate member being intermittently actuated by the cam means whereby said arcuate member is oscillated about its pivot to move the shoe means in an arcuate path about the axis of the bell crank pivot to oscillate said one of the shafts through an angle proportional to the arc of movement of the shoe means.

7. In feed change mechanism, in combination, a first shaft, cam means on the first shaft, a second shaft, a gear, operative connections between the gear and one of the shafts, a sector, means to position the sector for movement in an arcuate path about an axis, lever means pivotally mounted on the sector, a toothed segment on said lever means and in mesh with the gear on one of the shafts, guide means on the lever means, an elongated member formed with a groove in its

lower surface, means to pivotally mount one end of the elongated member, and means normally urging the other end of the elongated member toward the cam, said groove receiving the guide means on the lever means, said arcuate member being intermittently actuated by the cam means whereby said elongated member is oscillated about its pivot to move the guide means in an arcuate path about the axis of the bell crank to oscillate one of the shafts through an angle proportional to the arc of movement of the shoe.

8. In feed change mechanism, in combination, a first shaft, cam means on the first shaft, a second shaft, gear means loosely mounted on one of the shafts, one-way driving means between the gear means and one of the shafts, a sector, means to adjustably position the sector in an arcuate path about the axis of one of the shafts proportional to the desired angular rotation of a shaft, a bell crank pivotally mounted on the sector, operative connections between one arm of the bell crank and the gear means, guide means on the end of the other arm of the bell crank, an arcuate member, coacting guide means on the arcuate member, means to pivotally mount one end of the arcuate member, and means normally urging the other end of the arcuate member toward the cam, said arcuate member being intermittently actuated by the cam means whereby said member is oscillated about its pivot to oscillate one of the shafts through an angle proportional to the arc of movement of the guide means.

9. In feed change mechanism, in combination, a first shaft, cam means on the first shaft, a second shaft, gear means, one-way driving connections between the gear means and one of the shafts, a sector, means to adjustably position the sector through a predetermined movement proportional to the desired angular rotation of one of the shafts, lever means pivotally mounted on

the sector, operative connections between the lever means and the gear means, a pivoted guide member, coacting guide means between the lever means and the guide member, and means normally urging the guide member toward the cam, said guide member being adapted to be intermittently actuated by the cam means whereby said guide member is oscillated about its pivot to move the coacting guide means in an arcuate path about the said axis to oscillate one of the shafts through an angle proportional to the arc of movement of the coacting guide means.

10. In feed change mechanism, in combination, a power shaft, a cam on the power shaft, a driven shaft, a gear loosely mounted on the driven shaft, one-way clutch means between the gear and the driven shaft, a toothed sector, means to support the toothed sector for movement in an arcuate path about the axis of the power shaft, a bell crank pivotally mounted on the toothed sector, a toothed segment on one arm of the bell crank and in mesh with the gear on the driven shaft, a shoe pivotally mounted on the end of the other arm of the bell crank, an arcuate member formed with a groove in its lower surface, means to pivotally mount one end of the arcuate member, means normally urging the other end of the arcuate member toward the cam, said groove receiving the shoe on the bell crank, and a roller pivotally mounted on the other end of said arcuate member for intermittent actuation by the cam whereby said arcuate member is oscillated about its pivot to move the shoe in an arcuate path about the axis of the bell-crank pivot to oscillate the bell crank and thereby the driven shaft through an angle proportional to the arc of movement of the shoe, a carriage feed shaft and clutch means between the driven shaft and the carriage feed shaft.
